BANDEAU

Henry Rasch, Englewood, N. J.

Application August 11, 1944, Serial No. 548,995

3 Claims. (Cl. 2—42)

1

This invention relates to bandeaux and more particularly to a construction affording adjustable support regardless of different requirements of individual wearers.

The general object of the invention is to provide an improved bandeau construction which will assure an attractive outward appearance, with a substantially identical contour on both sides of the wearer, despite the fact that each side may require support to a different degree.

Another object of the invention is to provide a method of positioning removable filler cone members, so that comfortable yet snug fit will be provided by bandeaux of the same size fitted on women of different size.

A feature of the invention resides in the provision of an outer permanent breast formation element, in combination with an inner adjustable breast support. The outer element provides a desired contour effect while the inner support may assume different positions to provide a snug fit in supporting position.

Another feature of the invention resides in the provision of an intermediate retaining member between the outer breast formation element and the inner adjustable support. Said intermediate retaining member is fastened at seams connecting it to the outer formation element. A filler cone may readily be inserted behind the retaining member so that it assumes a substantially immovable position between the outer formation element and the inner adjustable support. The use of such filler cones not only provides improved appearance, but adds to the support required inasmuch as it takes up that space which results between the inner and outer members where the inner member is pulled up due to lack of fullness in a person of smaller size.

Another feature of the invention resides in the provision of substantially identical adjustable supporting and fixed formation elements for each side of the wearer combined, however, with means enabling each of the sides to be adjusted as desired to provide support in different degrees and yet retain the same outward appearance on both sides of the wearer.

Another feature provides for an adjustable slide strap support for each inner adjustable breast support so that said support will automatically be pulled up to a desired degree depending upon the requirements of the wearer for support. In other words, said slide strap arrangement enables the inner adjustable support to ride up or slide down to give required support and enhance the adaptability of the bandeau for wearers of different size, without causing discomfort.

Another feature covers the use of cones which may act as fillers as well as formation elements to give a desired outward appearance, and yet 60

2

be so positioned as to enable ready removal for replacement whenever desired.

Further features covering manner of assembly, adjustability for different waist sizes and making for ease, simplicity, economy and comfort, and adding to the desirability of employing the same bandeau during a longer period than existing prior constructions, will be more apparent from the following description of one form of the invention to be read in connection with the accompanying drawings in which—

Fig. 1 is a perspective view showing, in part, the outside of applicant's bandeau in assembled form;

Fig. 2 shows, in part, the rear view of said bandeau with the inner adjustable supporting elements turned down to show the retaining members;

Fig. 3 is a perspective view of a filler cone;

Fig. 4 shows one form of sliding tape arrangement for enabling the inner adjustable support to be raised and lowered, depending upon the requirements of the wearer;

Fig. 5 is a diagrammatic sectional view showing the relation of the permanent outer formation element, the inner adjustable supporting element, the filler cone, the retaining member therefor, and the self-adjusting tape arrangement; and

Fig. 6 is a perspective view showing applicant's bandeau in assembled form, looking toward the inner side thereof.

Considering the drawings, similar designations referring to similar parts, numeral 1 designates in general a bandeau or brassière structure. In Fig. 1 the outside of said structure is shown, in part, having permanently fixed breast formation elements 8 adapted to fit each side of the wearer and stitched by seams 9 to portions 10, 11 and 12 constituting the waist encircling assembly of the bandeau. While for economy of construction three elements 10, 11 and 12 are employed, applicant may combine said elements 10, 11 and 12 in one piece, if desired. Lower seam 13 and upper seam 14 provide the supporting and finishing characteristics required for the assembly making up the garment. Extension 15 on portion 10 is provided with a hook device 16 for fastening into eyes 17 provided in extension 18 attached to the end of portion 12. Such adjustment enables the bandeau to fit wearers having different waist sizes without the need for elastic inserts.

Considering Fig. 2, which is a view looking toward the inner side of the bandeau, retaining member 19 is stitched at each side of the bandeau at seam 14 to each element 8. Thus, its top edge is fixed. Its opposite sides are also stitched to opposite edges 20 of seam 9. The lower edge 21 is free and unstitched.

Inner adjustable breast supports 22 are held by seams 9 at that portion of the seam as more clearly shown in Figs. 2 and 6 and designated 23 in Fig. 6. In effect, the lower edge of each adjustable support 22 forms a curve held by seam 23 and overlapping retaining member 19. In effect, seam 23 commences a slight distance above the terminating point of edges 20 of the retaining member 19.

Each inner adjustable support 22 has a fold 10 24 to give it fullness and a similar fold 25 may be provided in outer element 8.

The upper edge 26 of inner support 22 is in the form of a curve as shown in Fig. 6 and is free. In Fig. 2, the upper edge is shown folded down 15 so that the lower edge 21 of retaining member 19 may be seen.

The inner adjustable support 22 may have at its upper tip a slide link 27 as shown in Fig. 2. This may fit within a loop 28 at the end of self-adjusting tape 29 whose other end is fixed to the tip 30 of outer formation element 8. In Fig. 6 both ends of self-adjusting tape 29 are stitched so that in this case there is no slide link 27 or loop 28. Instead, one end of the self-adjusting 20 tape 29 is stitched to the tip of inner support 22 as shown by the numeral 31 in Fig. 6 and the other end is stitched to tip 30 of the outer element 8.

The self-adjusting tape 29 is actually a small 30 strap fitted on the lower bar of buckle 32 so that it rides on the bar. Shoulder straps 33 have their rear edges 34 fastened to the upper seams of portions 10 and 12, whereas the other edge is adjustably folded within the upper part of buckle 35 32 as shown in Figs. 2 and 4 so that each strap 33 may be lengthened or shortened as desired.

Filler cone 35 as shown in Fig. 3 may readily be inserted in substantially fixed position against formation elements 8. This is easily done by pulling down the upper edges 26 of the inner breast supports 22 and inserting one or more cones under retaining member 19. The position of such cones between the retaining member and the formation elements 8 assures a non-shifting position of the filler cones and yet enables ready removal for replacement. Thus, the bandeau may be washed as desired and then new filler cones inserted. Also, different numbers of filler cones may be used depending upon the individual requirements of different wearers. A desirable full appearance is, therefore, assured.

Since the upper edge of adjustable support 22 is in the form of a long curve and since this is connected to self-adjusting tape 29, the inner support 22 will ride up to a required degree depending upon the size of the wearer and the fullness to be supported. As a result, the upper edge will form a shallow or a full inner pocket depending upon the size of the wearer. Its support characteristics will be substantially equivalent regardless of differences in fullness; and the adjustment will take place automatically depending upon the degree to which the adjustable inner support 22 will freely ride on the lower slide bar 60 of buckle 32.

Applicant thus provides a self-adjusting, hygienic bandeau which gives the permanent full effect desired from the standpoint of outer appearance combined with adjustability of support 70 and ready removability of filler members.

Since applicant's construction may be varied by modifications in cut and combination of the

various parts, and by modification in pattern without departing from the principles disclosed, no limitation is made with respect to precise details of design; and all equivalent structures are deemed covered within the purview of the appended claims.

I claim:

1. In a bandeau, the combination of an outer pocket member having substantially a fixed contour, a retaining member fixed within the outer pocket member, said retaining member being adapted to cover the upper portion of the breast of a wearer and to retain a filler cone in position adjacent said outer pocket member, a filler cone disposed adjacent said outer pocket member and being held in desired position by said retaining member, and an inner pocket member adapted to cover substantially all of the breast of a wearer and overlapping said retaining member, said inner member having a fixed bottom edge and a free top edge, said free top edge being held in such manner that it is self-adjusting depending upon the breast size to be supported.

2. In a bandeau, the combination of an outer 25 pocket member having substantially a fixed contour, a retaining member fixed within the outer pocket member, said retaining member being adapted to cover the upper portion of the breast of a wearer and to retain a filler cone in position adjacent said outer pocket member, a filler cone disposed adjacent said outer pocket member and being held in desired position by said retaining member, and an inner pocket member adapted to cover substantially all of the breast of a wearer and overlapping said retaining member, said inner member having a fixed bottom edge and a free top edge, a band connecting said inner and outer pocket members, a slide bar, said band being supported on said slide bar, and a shoulder strap fitted to a retaining means including said slide bar.

3. In a bandeau, the combination of a pair of outer pocket members having substantially fixed 45 contours, retaining members fixed within the outer pocket members, each retaining member being adapted to overlie the upper portion of a breast of a wearer and to retain a filler cone in position adjacent said outer pocket member, filler cones disposed adjacent said outer pocket members and being held in desired position by said retaining members, adjustable inner pocket members adapted to support the breasts and to assume different positions to provide a snug fit thereover, said inner pocket members overlapping said retaining members, each inner member having a fixed bottom edge and a free top edge, and means connected to the free edges of said inner members for adjusting said members to a degree depending upon the breast size to be supported.

HENRY RASCH.
